PORTABLE ELECTRIC HEAD LAMP

Filed Oct. 22, 1938

UNITED STATES PATENT OFFICE

2,164,529

PORTABLE ELECTRIC HEAD LAMP

William F. Koepke, Guttenberg, N. J., assignor
of thirty per cent to Adolph Berg, New York,
N. Y.

Application October 22, 1938, Serial No. 236,491

2 Claims. (Cl. 240—59)

This invention relates to portable electric head lamps and is an improvement over the lamps shown in my Patents Nos. 2,079,075 and 2,099,167.

5 An object of the present invention is to provide an electric head lamp that is simple and compact in construction.

Another object is to provide a casing for such a lamp that is characterized by fewness of parts.

10 Another object is to provide such a lamp with simple and positive switching mechanism.

A further object is to provide such a lamp that is easily assembled and disassembled.

15 Other objects and advantages will be apparent from the description thereof to follow taken in connection with the accompanying drawing in which—

Fig. 1 is a plan view of the improved electric head lamp with associated battery casing and conductors.

20 Fig. 2 is a side view of the improved head lamp.

Fig. 3 is a longitudinal sectional view of the head lamp.

25 Fig. 4 is a horizontal sectional view of the head lamp with the lamp bulb removed.

Fig. 5 is a detail view of a conducting plate.

Fig. 6 is a sectional view on the plane of the line 6—6 of Fig. 3, showing the parts in open circuit position.

30 Fig. 7 is a view similar to Fig. 6 but showing the parts in closed circuit position.

Fig. 8 is a spread perspective view of the contact members.

35 Fig. 9 is a detail view partly in section showing the movable switch member in open circuit position.

Fig. 10 is a detail view partly in section showing the movable switch member in closed circuit position.

40 Fig. 11 is a perspective view of a contact member.

My improved electric lamp may be operated by a battery such as shown in my above named patents. This battery comprises a cylindrical casing 45 for housing batteries 16. The open end of the casing is closed by a screw threaded cap 17. This cap is provided with a socket device with suitable contacts, one of which includes a central post 18 which engages the batteries, and the other of

50 which is in electrical connection with the cap 17. The socket has suitable openings in line with the contacts to receive the prong members of an ordinary electrical plug 19 which conducts the current from the battery by means of the conductors 55 20 and 21.

The lamp comprises a hollow casing which may be formed of Bakelite or other suitable insulating material and comprises two parts 22 and 23 connected by pins 24 or the like. The base is formed with a curved outer surface 25 to conform to the curvature of the forehead of the user and an inner semi-circular floor portion 26. End walls 27 and 28 of parts 22 and 23, respectively, are formed integrally with the base and each is provided with an inner socket portion or bearing member 29.

A hollow cylindrical or barrel shaped member 30 of the same material as the casing is positioned between the end walls 27 and 28 and has its ends 15 loosely mounted in the socket bearings 29, the remainder of the barrel loosely engaging the semi-circular floor portion 26 whereby said barrel may be rotated relatively to the casing member. This barrel shaped member 30 is provided with a circular opening 31 in its upper wall. The end walls 32 and 33 of this barrel are formed with openings 34 and 35, respectively, which are in alignment with openings 36 and 37, in the end walls 27 and 28, respectively of the casing.

20 Mounted in the barrel 30 against the end wall 33 is a metal contact member 38 as shown in Fig. 11 comprising a disk 39 and an elongated strip 40 seated on the floor of the barrel and extending inwardly toward the center thereof as shown in Fig. 3. The disk 39 has a central opening 41. Mounted in the other end 32 of the barrel is another metal contact member 42. This contact 42 comprises a disk 43 with a central opening 44 and an elongated strip 45 provided with an off-set portion 46 supporting a ring shaped plate or socket 47 which is provided with a screw threaded opening 48. The socket 47 may be provided with a peripheral downwardly extending lug 49 which engages a part of the wall of the base and helps to seat the contact 42 and prevent it from moving. The socket 47 is positioned above and spaced from the strip portion 40 of contact 38 with its opening 48 directly in line with said strip 40. Disk 43 is provided with a slotted portion 50 in its periphery, which slotted portion is provided with a straight wall 51 and slanted end wall 51' as shown in Figs. 8 and 9.

Extending through the aligned openings 37 and 35 of end walls 28 and 33, respectively, and through opening 41 of contact member 38 is a stem or post 52, which is square in cross section and is provided with a groove 53 adjacent its outer end. On the outer end of the stem 52 is supported a plate 54, one wall of its square shaped open-

25

55

ing 55 being positioned in the groove 53 so that said plate and stem are interlocked. One end of the plate 54 supports a terminal screw 56 for connecting one end of conductor 20. A spiral spring 57 surrounds the inner end of the stem 52 and has one end fastened to the inner end of the stem and its other outer convolution impinges against the disk 39 whereby said stem 52 is urged inwardly of the barrel and the disk 39 and conducting plate 54 are clamped to the end walls 33 and 28, respectively.

A post or stem 58 similar in construction to stem 52 extends through the aligned openings of end walls 27 and 32, respectively, and through aligned opening 44 of disk 43 of contact 42. A conducting plate 59 is supported and interlocked on the outer end of stem 58 similar to plate 54, and a terminal screw 60 connects the plate with conductor 21.

20 Mounted on the stem 58 inside the barrel and inwardly of the disk 43 is a metal finger member 61 having a lug or nose portion 62 extending outwardly toward disk 43. An insulating washer 63 separates finger member 61 from disk 43. A spiral spring 64 surrounds the inner end of stem 58 and has one end fastened to the inner end of said stem and its outer convolution impinging against finger member 61 normally urging the stem inwardly and the finger piece outwardly so that its lug 62 is normally positioned in the slotted portion 50 of the disk 43 and out of contact with said disk 43. The spring 64 also normally clamps the disk 43 and plate 59 to the end walls 32 and 27, respectively.

35 Mounted in the socket 47 of contact member 42 is a lamp bulb 65, the central terminal of which engages the contact strip 40 of contact 38, the other terminal of which lamp bulb is in engagement with the contact 42 through the socket 47. A reflector member 66 surrounds the lamp bulb and has its outer edge positioned in the central opening 31 of the barrel member 30. A magnifying lens 67 is seated in the outer edge of the reflector and said reflector and lens are 40 clamped to the wall of the central opening of the barrel by means of a wire spring member 68.

50 In order to protect the connections between the conductors 20 and 21 and conducting plates 54 and 59, respectively, insulating covers 69 and 70, respectively, of rubber, may be provided. These covers also permit easy sliding movement of a clip 71 which may be slidably supported on the conductors 20 and 21 whereby said conductors may be held in adjusted looped position around 55 the head of the user of the lamp, the lamp being mounted on the forehead and the conductors 20 and 21 looped around the head and held thereon by the clip 71.

60 The barrel 30, contacts 38 and 42, and lamp bulb and associated parts turn in unison whereas the stems 52 and 58 and the finger piece 61 remain stationary.

65 The circuit through lamp bulb 65 is as follows: central terminal 18 of batteries 16, one contact of plug 19, conductor 20, plate 54, stem 52, contact 38, central terminal of lamp bulb 65, side terminal of lamp bulb 65, contact 42, finger member 61, stem 58, conducting plate 59, conductor 21, other contact of plug 19 to the other terminal of batteries 16.

70 In using the improved head lamp, the casing is placed on the head of the user so that the curved portion 25 of the base is against the forehead. The casing is clamped to the forehead by means of the clip 71 restricting the opening be-

tween the conductors 20 and 21. When the barrel is in straight position such as shown in Fig. 6, the contact member 61 is in "on" position and remains in "on" position when tilted to one side, such as when tilted downwardly, but when tilted to the opposite side, such as shown in Fig. 7, the slotted portion 50 of disk 43 is moved into alignment with the lug 62 of member 61 and breaks the circuit putting out the lamp bulb. Movement of the barrel to the "off" position is limited by the barrel coming into contact with the side walls of the casing before the lug 62 engages the straight wall 51 of the slot 50.

I claim:

1. A portable electric head lamp including a 15 casing, a hollow barrel shaped member rotatable in the casing, a contact member having a disk portion positioned against the inner surface of one end wall of the barrel and having a strip portion extending along the bottom of the barrel to the center thereof, another contact member having a disk portion against the inner surface of the other end wall and having a strip portion and a socket portion, said socket portion being spaced from the first named strip portion but in alignment therewith, the disk portion of said last named contact member having a slotted portion in its periphery, said contact members being movable with said barrel shaped member, a fixed contact member in the path of movement 20 and adapted to be engaged by the last named contact member and a lamp bulb in said socket portion and having its central terminal in engagement with said first named strip, said fixed contact member being so arranged relative to 25 said last named contact member that rotation of said barrel shaped member in either direction will cause engagement of said contact members and close the circuit through said lamp bulb.

2. A portable electric head lamp comprising a 40 cylindrical metal casing, a battery in said casing, a removable metal cap on one end of the battery casing, a socket carried by said cap, contacts on said socket, one of said contacts being electrically connected to one terminal of the battery, 45 the other of said contacts being electrically connected with the metal cap, a plug mounted on said socket and having its prongs in electrical connection with the contacts of the socket, a hollow lamp casing formed of insulating material 50 and having a curved base portion and end walls, a barrel shaped member of insulating material 55 rotatably mounted in said casing, said barrel and casing having aligned openings in their end walls, metal posts extending through the said aligned openings, a contact member having a disk portion connected to one of said posts and having an integral strip portion extending along the bottom of the barrel to the center thereof, another contact member having a disk portion connected to 60 the other of said posts and having an inwardly extending strip portion and a socket portion, said socket portion being spaced from the first named strip portion but in alignment therewith, the disk portion of said last named contact member having a slotted portion in its periphery, said contact members being movable with said barrel shaped member, said posts being stationary on the casing, a fixed contact member spaced from said last named contact but having a nose portion in 65 the slotted portion thereof and adapted to engage the last named contact member, a lamp bulb in said socket portion having its central terminal in engagement with said first named strip, the other terminal of said bulb being in engagement 70 with the nose portion of the last named contact member.

with said second named strip, a conductor electrically connecting one of said plug prongs with the first named strip portion, another conductor electrically connecting the other of said plug prongs with the second named strip, and switching mechanism for placing the contact strips in electrically conductive relationship with the conductors, said mechanism including a post connected to one of said conductors, and a metal

finger member mounted on said post and normally having a nose portion in the slotted portion of said second named contact member and in alignment with said contact member whereby movement of the latter will cause engagement of the finger member and said latter contact member for closing the circuit. 5
